The ornamental design for a compact applicator for a topical astringent disinfectant, as shown and described.

DESCRIPTION

FIG. 1 is a perspective view showing the top, one side and the front of the compact applicator for a topical astringent disinfectant which forms our invention;

FIG. 2 is a rear elevational view thereof;

FIG. 3 is a front elevational view thereof;

FIG. 4 is a top plan view thereof;

FIG. 5 is a side elevational view thereof, this side and the opposite side being of identical design; and,

FIG. 6 is a bottom plan view thereof.
